CONTROL MECHANISM FOR GAS BURNERS

George A. Guenther, Buffalo, N. Y., assignor to
Leon H. Ballou, Lockport, N. Y.

Application January 6, 1941, Serial No. 373,245

5 Claims. (Cl. 236—84)

This invention relates to a control mechanism for gas burners of the character shown in Letters' Patent of the United States, No. 2,134,083 in which a combustion chamber containing the burner is subjected to the suction effect of an exhausting device and gas is supplied to the burner so long as the burner is in operation but the gas supply to the burner is stopped when the burner is extinguished.

In the control mechanisms of this type as heretofore constructed the valve device controlling the supply of gas to the burner was liable to chatter and work irregularly especially during the starting operation of the burner. Furthermore the diaphragm of this gas supply valve device was exposed to a large extent to contact with raw gas so that the same would deteriorate unduly rapidly and also become coated with dirt drawn in with the air and also with a sticky film resulting from the separation of moisture in the gas. Moreover, some of the dirt and film would be deposited on the cooperating surfaces of the closures of the control valve of the gas supply and cause the same to stick and operate erratically.

It is the object of this invention to provide a control mechanism for gas burners of this character which avoids the above mentioned unsatisfactory results by means which are comparatively simple, not liable to get out of order and can be manufactured and maintained in operative condition at low cost.

In the accompanying drawings:

Fig. 1 is a front elevation, on a reduced scale, of a gas heater embodying one form of this invention.

Fig. 2 is a top plan view of the control mechanism, on an enlarged scale, and partly in section, taken on line 2—2, Fig. 1 looking downwardly.

Fig. 3 is a vertical section, taken on line 3—3, Fig. 2.

Fig. 4 is a vertical section, taken on line 4—4, Fig. 2 but showing the bypass conduit shifted slightly from the position shown in Fig. 2 for the purpose of diagrammatically more clearly illustrating the invention.

Fig. 5 is a view similar to Fig. 2 but showing a modified form of this invention.

Fig. 6 is a top plan view, on a reduced scale, of the structure shown in Fig. 5, and taken on line 6—6 in the same.

Fig. 7 is a fragmentary vertical section, on an enlarged scale, taken on line 7—7, Fig. 6.

In the following description similar reference

characters indicate like parts in the several figures of the drawings.

Although this invention is applicable to gas heaters of various forms that shown in Fig. 1 as a satisfactory example is constructed as follows:

The numerals 10, 10 represent the two upright sections of a heat radiator which are separated by an intervening space or gap and which are adapted to receive hot gases through inlets 11, 11 arranged on the opposing inner sides of the upper ends thereof while the cooled gases are discharged through outlets 12, 12 arranged on the opposing inner sides of their lower ends. A partial vacuum is maintained in these radiator sections for withdrawing the spent heating gases therefrom by means of a suction fan 13 which is driven by an electric motor 14 and which has its inlet connected with one end of a suction conduit 15 while the opposite end of this conduit is provided with branch pipes 16 connected with the gas outlets of the radiator sections.

The motor is supplied with an electric current from any suitable source by main feed lines or wires 9, 9, and may be controlled by any suitable form of hand switch. On its upper part each of the radiator sections is provided with a safety vent 17 which is normally closed by a door 18 pivoted at its lower end to the respective radiator section and held in its closed position over the safety vent 17 by the suction of the fan but which will move by gravity into a position which opens this vent the instant the suction of the fan on the radiator is arrested.

The numeral 19 represents a combustion chamber which is arranged in the space between the sections of the radiator and has the opposite sides of its upper end connected by outlets 20, 20 where the hot gases in the combustion chamber are conducted to the inlets 11 of the radiator section. Within the lower part of the combustion chamber is arranged a gas burner 21 which burns a combustible fluid mixture of gas and air delivered thereto by a delivery pipe 22 extending vertically through the bottom of the combustion chamber and communicates with the lower end of the gas burner 21.

The mechanism for controlling the supply of combustible fluid to the burner in accordance with this invention is constructed as follows:

The numeral 23 represents the body of an air regulating valve which communicates with an air supply pipe 44 forming a downward extension of the combustible mixture delivery pipe 22 and through which air from the exterior of the combustion chamber is supplied to the lower end of

the combustible mixture conduit 22. The air regulating valve includes a closure member 24 whereby the amount of air passing through this valve may be regulated. Raw gas is supplied to the mixture conduit 22 by a gas supply conduit having its outlet portion 25 opening into the mixture conduit 22 between the air supply valve 23 and the gas burner and arranged at an angle thereto so that the adjacent parts of the mixture conduit 22 and the outlet portion 25 of the gas supply conduit converge toward the gas burner, as shown in Figs. 1, 4 and 5. Safety means are provided which cause the gas supply conduit to be opened when the fan exerts a suction effect on the burner but which causes the gas supply conduit to be closed when the suction of the fan on the burner is arrested. These safety means include a safety valve casing 26 having an inlet 27, which communicates with a nipple 28 forming an intermediate part of the gas supply conduit, an outlet 29 communicating with the discharge end 25 of the gas supply conduit, a port or seat 30 arranged between the inlet 27 and the outlet 29, and a closure 31 movable downwardly to close the port 30, as shown by full lines in Fig. 4, and upwardly to open the same, as shown by dotted lines in the same figure. Below the safety valve casing 26 are arranged the means for actuating the safety valve closure 31 in response to the suction effect of the fan and the cessation of the suction effect of the same. These suction responsive means include a suction chamber 32 formed in a housing 33 which may be connected with the underside of the safety valve casing 26 by a vertical neck 34 and containing a central operating passage having an upper wide part 35 which communicates with the outlet 29 of the valve housing, a lower narrow part 36 which communicates with the suction chamber 32, an upwardly facing sealing port or seat 37 arranged between the lower end of the passage section 35 and the upper end of the lower passage section 36 and a downwardly facing sealing port or seat 38 arranged at the lower end of the lower passage section 36, as shown in Fig. 4.

The underside of the suction chamber 32 is formed by a movable wall or diaphragm 39, the upper side of which at times is exposed to the suction effect of the fan 13 for moving this diaphragm upwardly, as shown by dotted lines in Fig. 4, while the underside of the same is exposed to outer atmosphere so that this diaphragm will drop by gravity, as shown by full lines in this figure, when the suction effect of the fan on the upper side of the same ceases. The safety valve closure 31 is raised and lowered in response to the rise and fall of the diaphragm by means of an upper operating valve stem 40 which projects from the safety valve closure 31 downwardly into the upper passage section 35 and a lower operating valve stem 41 arranged in the lower passage section 36 and engaging its upper end with the lower end of the upper valve stem 40 while its lower end engages with the central part of the upper side of the diaphragm. At its upper end the lower valve stem 41 is provided with a ball-shaped sealing closure 42 which is adapted to engage with the upper seat 37 while the lower end of the lower valve stem is provided with a ball-shaped sealing closure 43 which is adapted to engage the lower seat 38. Communication is maintained between the suction chamber 32 and the air supply conduit 44 at a point between the air regulating valve 23 and the outlet part 25 of the

gas supply conduit, this being accomplished, for example as shown in Fig. 4, by an annular air chamber or vent passage 45 formed in the neck 34 and communicating by longitudinal air or vent passages 46 in said neck with the suction chamber 32, and an air pipe or conduit 47 connected at one end with said annular chamber 45 and at its opposite end with said air pipe 44. The clearance between the parts 35, 36 of the operating passage and the operating valve stems 40, 41 is such that the same do not engage with each other thereby ensuring free movement of the means for transmitting motion from the diaphragm to the safety valve closure 31 and causing this mechanism to operate promptly and with certainty.

When the motor 14 and fan 13 are not in operation no suction is produced on the combustion chamber 19 and the burner or burners therein and no gas will be supplied to the latter due to the closure 31 of the safety valve being dropped into its closed position at which time the diaphragm is also in its lowered position owing to the absence of any upward suction thereon and direct communication between the outlet 29 of the safety valve and the suction chamber 32 above the diaphragm being cut off by the descent of the lower valve stem 41 whose upper ball closure 42 engages the seat 37 between the upper and lower passage parts 35, 36, as shown by full lines in Fig. 4. While the parts are in this position it is impossible for any gas to pass through the supply conduit to the burner and flood the heater and create a dangerous condition; it is also impossible for any gas passing from the outlet side of the safety valve casing or body into the suction chamber 32 and deteriorating the diaphragm or interfering with its operation; and dirt is also prevented from lodging on the upper valve seat 37 which otherwise might produce faulty engagement of the upper closure 42 therewith and possible downward leakage of gas past the same to the diaphragm.

If for any reason a back pressure of the combustible mixture should occur in the burner none of this mixture can reach the suction chamber 32 and injuriously affect the diaphragm because this chamber, the vent passages 45, 46, tube 47 and the tubular extension 44 below the outlet end 25 of the supply conduit only contain unmixed air which prevents gas from reaching the diaphragm and deteriorating the same and impairing or destroying the operation of the apparatus.

When the suction in the combustion chamber ceases the vent doors 18 of the radiator also open automatically by gravity thus releasing any gases which may be present in the radiator and combustion chamber.

When the suction on the burner, on the combustion chamber enclosing the same and on the radiator connected therewith is resumed by working of the suction fan, the vent doors upon being closed manually will be held shut, an upward suction will be produced in the combustible mixture delivery pipe 22, and the diaphragm will be lifted into the position shown by dotted lines in Fig. 4 due to the transmission of suction from the mixture delivery pipe 22 to the suction chamber through the pipe extension 44, pipe 47 and passages 45 and 46. The instant this occurs the lower valve stem 41 will be lifted and engage its lower ball closure 43 with the lower valve seat 38 so as to cut off direct communication between the interior of the safety valve casing and the suction chamber 32 and preventing gas from entering the suction chamber and deteriorating the diaphragm or impairing its operation by gumming.

up parts thereof due to deposit thereon of sticky residuum of the gas. As the diaphragm is lifted with the lower valve stem 41 the upper ball closure is also lifted from its seat 37 and an upward exhausting effect is produced in the lower and upper stem passages 36, 35 which prevents the accumulation of any gas therein and the safety valve closure 31 is lifted from its seat 30 by engagement of the upper end of the lower valve stem 41 with the lower end of the upper valve stem 40, thereby permitting flow of gas through the safety valve to the burner.

The amount of gas which might possibly pass downwardly through the passage parts 35, 36 to the diaphragm while the lower valve stem 41 is shifting from one position to another during starting and stopping of the burner is inappreciable and would not seriously affect the working of the mechanism.

It will now be apparent that in the operation of the apparatus the diaphragm of the safety valve is practically free from contact with gas at all times and the condition of the same is therefore not likely to be injuriously affected nor its operation impaired, thereby insuring satisfactory operation of the heater without serious interruption in its performance.

Any suitable means may be provided for automatically regulating the pressure of the gas supplied to the burner, this being accomplished by the valve mechanism which is shown in Figs. 1, 2 and 3 and which comprises a ball-shaped closure or valve 48 movable toward and from a seat 49 formed in the casing 50 of a regulating valve mechanism which communicates by a conduit 88 with the inlet part 10 of the gas supply conduit, and a stem 51 connecting the ball closure 48 with a regulating diaphragm 52 which is exposed on the discharge side of this regulating valve to the pressure of the gas passing through the supply pipe or conduit so that when the gas pressure exceeds the normal then the regulating valve will be closed more and when the gas pressure drops below normal the regulating valve will be opened more.

Means may also be employed for automatically shutting off the passage of gas through the supply conduit when the apartment being heated has reached the normal temperature desired and automatically resuming the supply of gas to the burner when the temperature of the apartment being heated drops below normal. The means for this purpose shown in Figs. 1, 2 and 3 comprise an electrically operated thermostatic control valve having a valve casing 53 the inlet 54 of which communicates with the outlet of the casing 50 of the automatic regulating valve and the outlet 55 of which normally communicates with the inlet 21 of the safety valve casing, a control valve closure 56 movable toward and from the seat 57 of the control valve between its inlet 54 and its outlet 55, a solenoid magnet having a core 58 connected with the valve closure 56 and a coil 59 surrounding said core, a thermostatic switch 60 arranged in the room the temperature of which controls the operation of the heater, and electric connections between said thermostatic switch, solenoid coil and electric current supply lines 9, 9 including a transformer 61 and a rectifier 62 similar to that shown in the patent hereinbefore mentioned.

When the temperature of the room containing the thermostatic switch 60 is normal or below normal the switch is closed and completes the

electric circuit of the solenoid magnet so as to hold open the valve closure 56 and permit gas to flow to the main burner 21 for maintaining a flame at the same, but when the temperature in this room rises above normal the thermostatic switch 60 of the circuit of the solenoid magnet causes the valve closure 56 to close and shut off the supply of gas to the main burner until the temperature of the room has again been reduced to normal. While the main burner 21 is extinguished a pilot light is provided for relighting the main burner when the supply of gas to the latter is resumed, this being accomplished for example by a pilot burner 63 arranged adjacent to the main burner and communicating by a pipe 64 with the inlet part 61 of the main gas supply conduit in rear of the automatic pressure regulating valve 48, 49, 50, as shown in Figs. 1 and 2.

20 Manual regulation of the amount of gas flowing to the main burner may be effected by a hand operated valve having a casing or body 65 tubularly connected with the gas supply conduit between the thermostatically controlled valve 53 and the safety valve 26 and a manually adjustable valve closure 66 of needle form for varying the size of the passage through this hand regulating valve, as shown in Fig. 2.

Instead of thermostatically controlling the flow 30 of gas to the main burner and operating the safety valve in the manner shown in Figs. 1-4, this mechanism, as shown in Figs. 5, 6 and 7, may be modified as follows:

The numeral 71 represents a thermostatically controlled suction or auxiliary vent chamber which communicates with the safety valve suction chamber 32 of the safety valve mechanism preferably by a passage 71a extending through the bottom of the thermostatic vent chamber 71 and the top of the safety valve suction chamber 32, as shown in Fig. 5. In its top this thermostatic chamber is provided with an atmospheric port 72 whereby its interior is placed in communication with the outer atmosphere and a suction port 73 which communicates with the air extension 44 of the combustible mixture discharge conduit 22 below the gas inlet 25 of the latter, this connection being preferably effected by a pipe 74, as shown in Figs. 5 and 6. Within the thermostat suction chamber 71 is arranged a valve lever 75 pivoted between its oppositely turning two arms on one of the walls of this chamber and provided on one of said arms with a valve closure 77 which controls the air port 73 while the other arm is adapted to shift a valve 76 which controls the vent port 72. Rocking of the valve lever 75 is produced by an operating lever 78 arranged within the suction chamber 71 and pivoted thereto at one end while its opposite end is connected with the valve lever, a spring 79 interposed between the lever 78 and the wall of the suction chamber 71 and operating to turn this lever downwardly, a solenoid core 80 connected with the operating lever 78 and adapted to raise the latter and a solenoid coil 81 enclosing the core 80 and arranged in an electric circuit which contains a thermostatic switch 82, similar to the switch 60, whereby this circuit is opened when the temperature in the room containing this switch rises above normal and closed when this temperature drops to or below normal.

In the modified construction of this invention, shown in Fig. 7, the neck 83 containing the means for transmitting motion from the diaphragm 39

to the safety valve closure 311 does not contain any air passages, thereby simplifying the construction, but it is to be noted that the safety valve closure 311, gas passages 351, 361, valve closures 421, 431, stems 401, 411, seats 371, 381 and associated parts are the same as the corresponding structural features shown in Figs. 1, 2 and 4.

When the solenoid magnet in the construction shown in Figs. 5 and 6 is deenergized due to opening of the thermostatic switch 82 when the room temperature rises above normal the diaphragm 391 drops and the safety valve 311 closes so that the gas supply to the main burner is shut off. When this occurs the solenoid core 80 has dropped and permitted the spring 79 to turn the levers 78 and 75 in the direction for opening the atmospheric vent valve 76 and close the suction valve 77 so that the exhausting effect produced on the main burner 21 by the suction fan 13 will not operate to lift the diaphragm 391 nor open the safety valve 311. When, however, the room temperature again drops to or below normal, the thermostatic switch 82 again closes the circuit of the solenoid coil 81 whereby the core 80 is lifted, the vent valve 76 is closed to cut off entrance of external air into the suction chamber 71 and the suction valve 77 is opened to permit upward suction from the mixture pipe 22 to the main burner and exert a suction effect through the pipe 74 on the diaphragm 391 so that the latter lifts the safety valve 311 from its seat and permits gas to flow through the main supply conduit to the main burner.

The vent valve closure 76 is preferably so organized that its stem projects downwardly into the path of the upper arm of the valve lever 75 so that the latter upon engaging this stem will open this closure, as shown in Fig. 5, but permit this closure to turn into a closed position when the respective arm of the valve lever 75 is disengaged from said stem. The throw of the solenoid core 80 is so controlled that its upward movement upon energizing the coil 81 will be limited by a stop 83 after the valve 76 is closed, but still leaving the valve lever 75 free, thereby enabling the core 80 to be held tightly at the end of its stroke by the pulling effect of the energized coil 81 and thus enable the vent valve 76 to close positively without liability of the solenoid magnet 80, 81 chattering as would be the case if the vent valve 76 closed first and the coil 81 would continue its attraction on the core to complete the stroke of the latter.

Accordingly the mechanism for operating the valves 77 and 76 are so organized that the solenoid core 80 engages the stop 83 before its movement during energizing of the coil 81 is arrested by any other parts and particularly before the lever 75 strikes any stationary part after closing the valve 76 and opening the valve 77.

It will be obvious from the foregoing explanation that the electromagnetically operated control means shown in Figs. 3 and 5 can be used interchangeably and that, in effect, the organization shown in Figs. 5, 6 and 7 is the equivalent of taking the chamber 71 from Fig. 5 and placing the same in the conduit 47 of Fig. 4 so as to form a part of this conduit between the air inlet 44 and the suction chamber 32.

In both forms of this invention the valve means associated with the stems, whereby motion is transmitted from the diaphragm to the safety valve, are so organized that raw gas is prevented

from reaching the diaphragm and corroding, gumming or otherwise injuriously affecting the same, thereby prolonging the life of this diaphragm and practically eliminating servicing of this burner control mechanism for maintaining the same in satisfactory operative condition.

Moreover the provision of the double valves 42 and 43 which close the sections 35, 36 of the operating passage when the diaphragm is either lowered or raised prevents the flow of any air or gas through this passage at all times and keeps this passage free from dirt and sticky deposits and therefore insures free action of the parts of the safety valve device.

I claim as my invention:

1. A safety valve device for gas burning heaters comprising a valve body having a gas inlet, a gas outlet and a safety port between said inlet and outlet, a suction chamber constantly disconnected from the inlet of said body but communicating with the outlet of said body close to said port by a near vent passage and remote from said port by a far vent passage and said suction chamber having a movable wall or diaphragm the inner side of which constantly faces said near and far passages and the outer side of which is constantly exposed to atmospheric pressure, a movable safety valve which controls said safety port, and means arranged in said near vent passage for transmitting motion from said wall or diaphragm to said safety valve and provided with a vent valve for controlling said near vent passage.

2. A safety valve device for gas burning heaters comprising a valve body having a gas inlet, a gas outlet and a safety port between said inlet and outlet, a suction chamber constantly disconnected from the inlet of said body but communicating with the outlet of said body close to said port by a near vent passage and remote from said port by a far vent passage and said suction chamber having a movable wall or diaphragm the inner side of which constantly faces said near and far passages and the outer side of which is constantly exposed to atmospheric pressure, a movable safety valve which controls said safety port, said near vent passage having outer and inner vent valve seats, a valve connection which is arranged in said near vent passage and whereby motion is transmitted from said wall or diaphragm to said safety valve, and inner and outer valves movable with said connection and adapted to alternately engage the respective inner and outer vent valve seats for closing said near vent passage in either position of said wall or diaphragm.

3. A safety valve device for gas burning heaters comprising a valve body having a gas inlet, a gas outlet and a safety port between said inlet and outlet, a suction chamber constantly disconnected from the inlet of said body but communicating with the outlet of said body close to said port by a near vent passage and remote from said port by a far vent passage and said suction chamber having a movable wall or diaphragm the inner side of which constantly faces said near and far passages and the outer side of which is constantly exposed to atmospheric pressure, a movable safety valve which controls said safety port, means arranged in said near vent passage for transmitting motion from said wall or diaphragm to said safety valve, said far vent passage having a far valve seat, a far vent valve cooperating with said far valve seat for controlling said far vent passage, and electromagnetic means for actuating said far vent valve.

4. A safety valve device for gas burning heaters comprising a valve body having a gas inlet, a gas outlet and a safety port between said inlet and outlet, a suction chamber constantly disconnected from the inlet of said body but communicating with the outlet of said body close to said port by a near vent passage and remote from said port by a far vent passage and said suction chamber having a movable wall or diaphragm the inner side of which constantly faces said 10 near and far passages and the outer side of which is constantly exposed to atmospheric pressure, a movable safety valve which controls said safety port, means arranged in said near vent passage for transmitting motion from said wall or dia- 15 phragm to said safety valve and means for controlling said far vent passage including a vent chamber forming part of said far vent passage and having an intermediate vent port and a final vent port, an intermediate rock lever having an intermediate vent valve for controlling said 20 intermediate vent port, a tilting final vent valve for controlling said final vent port having a stem which is engaged by said intermediate lever to be actuated thereby, a rock arm engaging said 25 rock lever, an electromagnetic shifting device having a movable member connected with said rock

arm, and an electric circuit containing a thermostatic switch which is operatively connected with said electromagnetic shifting device and whereby the latter is controlled in response to 5 said thermostatic switch.

5. A safety valve device for gas burning heaters, comprising a valve body having a gas inlet, a gas outlet and a safety port between said inlet and outlet, a suction chamber constantly disconnected from the inlet of said body but communicating with the outlet thereof by a constantly open passage and also adapted to communicate intermittently with said outlet by an openable and closeable passage, and said suction chamber having a movable wall or diaphragm the inner side of which is exposed to said constantly open passage and also to said openable and closeable passage and the outer side of which is constantly exposed to atmospheric pressure, a movable safety valve which controls said safety port, and means which are arranged in said openable and closeable passage and are adapted to transmit motion from said wall or diaphragm to said safety valve and which are provided with a valve device for controlling said openable and closeable passage.

GEORGE A. GUENTHER.
